(57) **CLAIM**

The ornamental design for a electric hair curling brush, as shown and described.

DESCRIPTION

FIG. 1 is a bottom, front and right-side perspective view of an electric hair curling brush, showing my new design; FIG. 2 is top, rear and left-side perspective view thereof; FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the electric hair curling brush and form no part of the claimed design.
